UNITED STATES PATENT OFFICE.

GEORGE M. SCHEBLER, OF INDIANAPOLIS, INDIANA, ASSIGNOR TO WHEELER & SCHEBLER, OF INDIANAPOLIS, INDIANA, A COPARTNERSHIP.

CARBURETER.

971,689.

Specification of Letters Patent.

Patented Oct. 4, 1910.

Application filed April 5, 1909. Serial No. 487,911.

To all whom it may concern:

Be it known that I, GEORGE M. SCHEBLER, a citizen of the United States, residing at Indianapolis, in the county of Marion and State of Indiana, have invented certain new and useful Improvements in Carbureters, of which the following is a specification.

The object of my invention is to produce certain details in construction of a carbureter by means of which the inward flow of air upon the valves will act uniformly thereon; by means of which the air valves may, under different speeds of the engine, admit varying supplies of air by the production of variable openings; by means of which the effect of movement of the throttle valve upon the fuel supply valve may be varied by proper adjustment, and to produce such further improvements in details of construction as shall be hereinafter pointed out.

The accompanying drawings illustrate my invention.

Figure 1 is a side elevation in partial vertical section; Fig. 2 a plan in partial horizontal section.

In the drawings, 10 indicates the float chamber of an ordinary and well known type, the flow of oil therefrom being controlled by means of a needle valve, the stem 30 11 of which is movable axially so as to vary the opening thereof relative to the position of the throttle valve 12 in a manner similar to that shown in my Patent No. 886,545.

In carbureters of the present time difficulty is experienced in the actuation of the air inlet valves owing to the fact that the incoming air tends to take the shortest path of travel past the air valves into the interior of the carbureter and, as the opening between the valve and the interior of the carbureting chamber has heretofore been formed along this shortest path, the incoming air acts upon one side of the valve more than it does upon the opposite side and thereby tends to tip or cant the valve and retard its movement. I have found in practice that this difficulty can be avoided by arranging between the valve chamber 31 and the air passage 32, which passes to the carbureting chamber 33, a baffle wall 34 which thus forms a pair of passages 35, 35 which supply passage 32 from diametrically opposite points 36, 36 communicating with the valve chamber 31. By this arrangement, 55 there being a suction upon the valve at dia-

metrically opposite sides, there is a uniform yield of the valve which thus insures a steady working of the valve and a uniform supply of air.

In practice difficulty has heretofore been experienced in so adjusting the single air valve that the carbureter will work satisfactorily not only upon high speeds but upon low speeds. In fact it is practically impossible, with the single valve to obtain satisfactory air admission throughout the range of speed of the engine. Difficulty has also been experienced by reason of the tendency of the valves to suddenly close and in order to obviate these two difficulties I provide the following construction: The air inlet 31 has an inwardly presented annular seat 52 upon which is seated an annular inlet valve 53. This valve 53 is carried by a spider 54 carried by a sleeve 55 which passes through a bearing 56 formed in the cylinder member 57. Secured to the lower end of sleeve 56 is a cylinder 58 which, at its lower end, is provided with a piston flange 59 fitting loosely in cylinder 60 forming part of the cylinder member 57. The cylinder 58 is provided with a head 61 against which a spring 62 acts, said spring resting upon an adjustable abutment 63, and tending to hold the annular valve 53 to its seat. A ball valve 64 forms a communication through piston 59 from cylinder 60. Fitted loosely within cylinder 58 is a piston 66 equipped with a ball valve 67 said piston being normally urged upward by a spring 68 which is considerably lighter than spring 62 and is engaged by an adjustable abutment 69 carried by head 61. Piston 66 is secured to the lower end of a valve stem 71 which passes up through sleeve 65 and carries a valve 72 which seats in the inner diameter of the annular valve 53. The pistons 59 and 66 fit their cylinders somewhat loosely, in the manner of ordinary dash pot pistons, and the ball valves 64 and 67 operate as ordinary valves in common dash pot constructions, the said pistons and cylinders merely forming dash pots for the valves 52 and 72 in order that, in their closing action, they may be a little more sluggish than in opening.

The operation is as follows: A suction induced in passage 32 affects chamber 31 upon diametrically opposite sides of stem 55 and valve 72 yields to permit an inflow of air through the annular valve 53 and the inflow

of air is uniform and there is no tendency to tip the valve 72 because there is no short passage from the valve to passage 32. If the suction within passage 32 is greater than can be supplied by a yield of valve 72 the annular valve 53 will also yield thus increasing the inlet so as to increase the supply of air entering the carbureter. The exact relation of the two valves may be adjusted by means of the adjusting screws 63 and 69. It will be readily understood that, as the valves 72 and 52 open, the air within the cylinders 58 and 60 respectively will pass out through the pistons quite readily past the valves 67 and 64 but on the return stroke the valves 64 and 67 will seat themselves and thus require the cylinders to be filled with air which will leak past the pistons and this leakage will be slow.

20 I claim as my invention:—

1. A carbureter comprising a mixing chamber, a supply passage, an inlet chamber, and an inlet valve in the initial portion of the inlet chamber, the supply passage leading from the inlet chamber at substantially diametrically opposite points.

2. A carbureter, comprising a main casing, having a mixing chamber, an air inlet chamber, an inlet valve in an initial portion of the inlet chamber, and a passage forming a connection between the air inlet chamber and the mixing chamber, and a guard 34 arranged between the inlet chamber and the air passage in the direct line between the air inlet chamber and the mixing chamber whereby the air passage is bifurcated adjacent the air inlet chamber and communicated with the air inlet chamber at substantially diametrically opposed points.

3. In a carbureter, an annular inlet valve, a hollow stem carrying said annular valve, a dash-pot piston carrying said stem, a dash-pot cylinder coöperating with said piston, a dash-pot cylinder formed in said piston, a

dash-pot piston mounted in said last mentioned cylinder, a stem carried by said last mentioned piston and extending through the aforesaid hollow stem, a valve carried by said stem and seated in the annular valve, and means for yieldingly holding said valves with different pressures to their seats.

4. In a carbureter, an annular inlet valve, a hollow stem carrying said annular valve, a dash-pot piston carrying said stem, a dash-pot cylinder coöperating with said piston, a dash-pot cylinder formed in said piston, a dash-pot piston mounted in said last mentioned cylinder, a stem carried by said last mentioned piston and extending through the aforesaid hollow stem, a valve carried by said stem and seated in the annular valve, a spring engaging the first mentioned piston, a second but lighter spring carried by said first mentioned piston and engaging the second piston, and means for independently adjusting the force of said springs.

5. In a carbureter, an annular inlet valve, a hollow stem carrying said annular valve, a dash-pot piston carrying said stem, a dash-pot cylinder coöperating with said piston, a dash-pot cylinder formed in said piston, a dash-pot mounted in said last mentioned cylinder, a stem carried by said last mentioned piston and extending through the aforesaid hollow stem, a valve carried by said stem and seated in the annular valve, a spring engaging the first mentioned piston, and a second but light spring carried by said first mentioned piston and engaging the second piston.

In witness whereof, I have hereunto set my hand and seal at Indianapolis, Indiana, this fourth day of March, A. D. one thousand nine hundred and nine.

GEORGE M. SCHEBLER. [L.S.]
